UNITED STATES PATENT OFFICE

PIPSAN SAARINEN SWANSON, OF BIRMINGHAM, MICHIGAN, ASSIGNOR TO PACKARD MOTOR CAR COMPANY, OF DETROIT, MICHIGAN, A CORPORATION OF MICHIGAN

DESIGN FOR A STEERING WHEEL

Application filed December 20, 1929. Serial No. 33,863. Term of patent 14 years.

To all whom it may concern:

Be it known that I, PIPSON SAARINEN SWANSON, a citizen of the United States, residing at Birmingham, county of Oakland, State of Michigan, have invented a new, original, and ornamental Design for Steering Wheels, of which the following is a specification, reference being had to the accompanying drawings, forming a part thereof, and in which—

Fig. 1 is a top plan view of a steering wheel incorporating my new design;

Fig. 2 is a side elevation of the same, partially in sectional diagrammatic outline substantially on the line 2—2 of Fig. 1, and Figs. 3, 4 and 5 are sectional views, in diagrammatic outline, substantially on the lines 3—3, 4—4, and 5—5, respectively, showing the shape of the steering wheel spoke.

I claim:
The ornamental design for a steering wheel, as shown.

In testimony whereof I affix my signature.
PIPSAN SAARINEN SWANSON.
